W. A. READE

TYPOGRAPH MECHANISM

Filed Dec. 8, 1920

Patented May 22, 1923.

1,455,835

UNITED STATES PATENT OFFICE.

WILLIAM A. READE, OF EVANSTON, ILLINOIS, ASSIGNOR TO LUDLOW TYPOGRAPH COMPANY, OF CHICAGO, ILLINOIS, A CORPORATION OF ILLINOIS.

TYPOGRAPH MECHANISM.

Application filed December 8, 1920. Serial No. 429,052.

To all whom it may concern:

Be it known that I, WILLIAM A. READE, a citizen of the United States, and a resident of Evanston, county of Cook, and State of Illinois, have invented a new and useful Improvement in Typograph Mechanism, of which the following is a specification, the principle of the invention being herein explained, and the best mode in which I have 5 contemplated applying that principle so as to distinguish it from other inventions.

The present improvements, relating, as indicated, to typograph mechanism, have more particular regard to the provision of means 15 whereby slugs or lines of type may be cast on which the characters are inclined, as in italics. I am aware that attempts have heretofore been made to adapt the Mergenthaler linotype and other similar typograph 20 machines for the casting of type bars of this sort, but no commercially successful device has even been achieved.

The present invention, accordingly, has at its object the provision of a novel form of 25 matrix bar, or matrix as it is commonly termed, which may be utilized in connection with the regular feeding and assembling mechanism of a standard linotype or equivalent machine. To the accomplishment of the 30 foregoing and related ends, the invention, then, consists of the means hereinafter fully described and particularly pointed out in the claims, the annexed drawing and the following description setting forth in detail certain mechanism embodying the invention, 35 such disclosed means constituting, however, but one of various mechanical forms in which the principle of the invention may be used.

40 In said annexed drawing:—

Fig. 1 is a front elevation of those parts of a typical linotype machine in connection with which my present improvement may be employed; Fig. 2 is a transverse section, on 45 a larger scale, through the mold and adjacent parts, the plane of the section being indicated by the line 2—2, Fig. 1; Fig. 3 is a front view of an assembled line of matrices as collected and held in position for 50 casting, similar to that shown in cross-section in Fig. 2; Fig. 4 is a rear view of a shorter assembly of matrices showing the faces that carry the intaglio type characters, such matrices appearing in their initial position, i. e. as first assembled; Fig. 5 is a

view similar to Fig. 4, but showing the matrices in a subsequent stage of their assembly, ready for casting; and Fig. 6 is a view of a single matrix on a larger scale than those shown in Figs. 4 and 5.

In the typical construction of linotype machine shown in Fig. 1, the font of special matrices employed in the casting of italics will be normally contained in suitable sections or compartments of the magazine 1. 60 From the latter they are received on the assembling belt 2, one at a time, and are assembled side by side in line, as shown in Fig. 4. As they are thus assembled, such line of matrices is delivered horizontally from the 65 elevator through the so-called intermediate channel 3 from the elevator 4, after the latter has been raised. From the channel 3 the line of matrices is transferred to a second elevator 5, which is raised into the position 70 indicated in dotted outline for this purpose, whereupon such elevator lowers the line into casting position adjacent the front face of the slotted mold 6, the latter being mounted in a disk 7.

All the foregoing parts are familiar elements in the construction of the machine referred to, as is also the mechanism whereby the matrices are subsequently lifted to the distributing mechanism; thence to be delivered again to the magazine 1. Since the present invention relates primarily to the form of the matrices and the manner in which they are assembled in line in the channel 3, and subsequently disposed for casting 75 adjacent the mold 6, it is not deemed necessary to further describe the unrelated parts of the general machine.

As shown in Fig. 2, in which a single matrix 10 appears held in proper casting 80 against the face of the mold 6, such matrix in side elevation resembles those in familiar use in commercial linotype work, such matrix consisting of a flat plate with an intaglio character 11 in its edge thus juxtaposed to the slot 12 in the mold. The character impression 11 in the case in hand is shown as formed in a depression 13 in such edge of the matrix, such depression being of greater width than the slot 12 so as to provide an enlarged body or head on the finished slug to support the raised character impressions when the cast is made. The sides of the depressions 13, as shown in Figs. 4, 5 and 6, are not, as ordinarily, disposed at 85

right angles to the longitudinal line of the matrix, but are inclined to such line at an angle corresponding to that which characterizes the particular style of italic character which it is desired to use. The character impression 11 in the bottom of the recess is of course correspondingly inclined in its several parts. The top and bottom edges of each matrix, in addition to being formed with surfaces 14, 14, that are normal to the median line or longitudinal axis of the plate composing such matrix, are formed with other surfaces 15, 15, that are parallel with the sides of the recess 13 in the casting edge of the plate. So, too, the shoulders 16 and 17 adjacent the upper and lower edges of the plate respectively are formed on their inner faces with surfaces 16^a, parallel with said surfaces 14, and with surfaces 16^b, parallel with said surfaces 15, it being by means of such shoulders that the matrices are sustained as they pass through channel 3.

In the preliminary assembly of the matrices as they are received from conveyor 2 and lined up on elevator 4, they rest on the normal faces 14, as shown in Fig. 4, in which position the character depressions are obviously not properly disposed to form a composite mold of the desired kind; however, by tilting such assembly of matrices so that the inclined surfaces 15 are brought into alignment, as shown in Fig. 5, the character depressions are then brought into proper line to form such composite matrix. For the purpose of thus tilting or inclining the matrices, a wedge block in the form of a blank matrix 20, having faces that incline at the proper angle to each other, is introduced at each end of the assembly, so that upon clamping the assembly between two abutments 21 and 22, as shown in Fig. 3, having faces normal to the line of assembly, all of the matrices bearing character impressions are tilted to the predetermined angle. For the purpose of spacing, other blank matrices 23, having parallel sides, may be introduced where desired in the line of assembled matrices, as shown in Figs. 4 and 5.

By reason of the angularly related faces 14 and 15 on the respective matrices, and the correspondingly angularly related faces 16^a and 16^b on the shoulders 16, the tilting of the assembled line may take place either while such matrices are resting on a flat surface or are sustained, by means of such shoulders, on a projecting rib such as the rib 25 on the face of the mold, and the oppositely disposed rib 26 on the face of the elevator 5.

It is to be understood that the particular method or means employed to preliminarily assemble in line my improved form of matrices is not limited to that hereinbefore described, i. e. to the conveyor and other parts 65 of the familiar linotype machine, such ma-

chine being illustrative only. Obviously such assembling may be accomplished directly by hand either in channel 3 or elevator 5 of such machine, or in other equivalent holder, and then after tilting the matrices and clamping them together in assembled condition, the slug may be cast therefrom in any suitable casting machine. It will further be understood that if required solely for use with my improved matrices, the clamping abutments may have their faces inclined, just as though the wedge-shaped plates 20 were integral therewith, and the use of such plates thus dispensed with.

It will be understood, further that no limitation is to be implied in the field of use of the present invention to the particular typograph machine hereinbefore specifically referred to but that the improvements in question may be employed in conjunction with various type-bar casting machines at present on the market, as, for example, with the well-known Ludlow typograph.

Other modes of applying the principle of my invention may be employed instead of the one explained, change being made as regards the details herein disclosed, provided the steps or means stated by any of the following claims or the equivalent of such stated steps or means be employed.

I therefore particularly point out and distinctly claim as my invention.

1. In typograph mechanism, a matrix bar having parallel sides and a character impression inclined with respect to such sides, said bar being formed with a plurality of relatively angularly inclined surfaces for alignment purposes.

2. In typograph mechanism, a matrix bar having parallel sides and a character impression inclined with respect to such sides, said bar being formed with a plurality of angularly related surfaces for alignment purposes, one such surface being at right angles to the sides of said bar and the other such surface being inclined to correspond with the inclination of such character impression.

3. In typograph mechanism, a matrix bar having parallel sides and a character impression inclined with respect to such sides, said bar also having a plurality of angularly related surfaces on its ends.

4. In typograph mechanism, a matrix bar having parallel sides and a character impression inclined with respect to such sides, said bar also having a plurality of angularly related surfaces on its ends, one disposed at right angles to such sides and the other inclined to correspond with the inclination of such character impression.

5. In typograph mechanism, a matrix bar having parallel sides and a character impression inclined with respect to such sides, said bar also having a laterally projecting

shoulder formed by the intersection of angularly related surfaces, substantially at right angles to the side.

6. In typograph mechanism, a matrix bar having parallel sides and a character impression inclined with respect to such sides, said bar also having a laterally projecting shoulder formed with angularly related surfaces, one disposed at right angles to such sides and the other inclined to correspond with the inclination of such character impression.

7. In typograph mechanism, a matrix bar having parallel sides and a character impression inclined with respect to such sides, said bar also having a plurality of angularly related surfaces on its ends, one disposed at right angles to such sides and the other inclined to correspond with the inclination of such character impression, and a laterally projecting shoulder formed with similar angularly related surfaces.

8. In typograph mechanism, a matrix bar having parallel sides and a character impression inclined with respect to such sides, said bar also having a plurality of angularly related surfaces on its ends, one disposed at right angles to such sides and the other inclined to correspond with the inclination of

such character impression, and a laterally projecting shoulder formed with similar angularly related surfaces adjacent each end formed with similar angularly related surfaces.

9. In typograph mechanism, the combination with a plurality of matrix bars having parallel sides and character impressions inclined with respect to such sides, of means adapted to retain said bars in line inclined at an angle to such line corresponding with the inclination of such character impressions.

10. In typograph mechanism, the combination with a plurality of matrix bars having parallel sides and character impressions inclined with respect to such sides, of guide means adapted to engage and retain said bars in line, said bars being formed with engaging elements whereby they may be thus retained either normal to such line or at an angle thereto, as desired, and means including wedges adapted to clamp said bars together and incidentally tilt same to such angle.

Signed by me, this 4th day of December, 1920.

WILLIAM A. READE.
